COMBINED PHONOGRAPH CONSOLE AND LOUD-SPEAKER UNIT OR SIMILAR ARTICLE

**Kenneth Russell Wilkes, Marcellus, N.Y., assignor to
General Electric Company**

Filed Apr. 29, 1971, Ser. No. 138,870

Term of patent 14 years

Int. Cl. D14—01

U.S. Cl. D56—4 R

FIG.1

FIG.2

FIG.3

FIG.4

FIG. 1 is a perspective view of the combined phonograph console and loudspeaker unit or similar article, in accordance with my design;

FIG. 2 is a front elevational view;

FIG. 3 is a side elevational view; and

FIG. 4 is a top plan view.

A rear view of the loudspeaker members is not shown, being substantially planar and non-ornamental.

I claim:

The ornamental design for a combined phonograph console and loudspeaker unit or similar article, as shown and described.
